UNITED STATES PATENT OFFICE.

ROY H. RICHARDSON, OF KANSAS CITY, MISSOURI.

WATER-ELEVATING APPARATUS.

964,693.

Specification of Letters Patent. Patented July 19, 1910.

Application filed May 6, 1909. Serial No. 494,448.

To all whom it may concern:

Be it known that I, Roy H. RICHARDSON, citizen of the United States, residing at Kansas City, in the county of Jackson and State of Missouri, have invented certain new and useful Improvements in Water-Elevating Apparatus, of which the following is a specification.

My invention relates to improvements in water elevators and has particular reference to devices adapted to elevate and deliver water from depressed points by air compression.

One of the objects of my invention is to provide an apparatus of this character by means of which a containing vessel is placed under an initially-provided pressure produced by the compression of air within the container, and controlling the outflow in such manner as to permit of a replenishment of the water within the container after the latter has been expelled by the action of the air pressure therein.

A further object is to provide a water container having a valved inlet at its bottom and also having a valve cage removably seated above the inlet and having a fixed connection with a removable cap carried at the upper end of the container, whereby the valve and its cage may be bodily withdrawn from the container for the purpose of repairs, the valve and cage being formed relative to each other in such manner that the valve will be seatable only when the cage is in proper position within the container.

Further objects of the invention are to provide an apparatus of this character which may be employed with containers of different shapes to enable the apparatus to be used in connection with water supplies of different forms, to construct an apparatus in which the entrance of the water into the container during the replenishing operation will not produce excessive currents of water, and to provide a construction which is simple and efficient in operation, durable in construction, and which can be manufactured and placed in position at a relatively low cost.

To these and other ends, the nature of which will be readily understood as the invention is hereinafter disclosed, said invention consists in the improved construction and combination of parts hereinafter fully described, illustrated in the accompanying drawings, and particularly pointed out in the appended claims.

In the accompanying drawings the figure is a view partly in section, showing the parts of my improved apparatus, the container being shown in section and as positioned 60 within a well.

The apparatus which forms the subject matter of my invention comprises substantially three elements, an air pump A, a water container B, and a pressure regulator C.

The air pump A is of any desired type, that shown in the drawings being what is known as a double acting pump operated by hand, the pump having a suitable pressure 70 gage a and provided with the usual inlet ports for the air; the entire structure of the pump, being of a general type, is not illustrated in detail.

The water container B may be of any desired configuration in cross section. The container may have its axis extending vertically or horizontally, dependent entirely on whether the container is to be located within a well or within a shallow stream, the 80 container shown in the drawing having a vertical axis and being supported in any suitable manner, as by pins b extending into the walls of the well and through openings formed in ears b' carried by the container; 85 if desired, the container may be suspended from the top of the well by means of chains or other suitable supporting connections carried by the ears b' and supported at the top of the well. Where the container is adapted to be placed within a stream, it may have its axis approximately horizontal, suitable supporting means, such as feet or other form of standard, being secured on the bottom of the container and formed of sufficient length 90 to maintain the container out of contact with the bed of the stream, this position being desired to permit of the presence of the water inlet structure presently described.

The container B is preferably formed to 100 provide a substantially air-tight structure, having a suitable top and bottom, these parts being shown as curved or dish-shaped, the curvature in the bottom being provided to partially inclose the external portion of the 105 water inlet, while the curvature of the top provides for an increased amount of air space.

The water inlet of the container is located at the bottom thereof and in the form of 110 container shown in the drawing, the bottom is provided with an opening adapted to re-

ceive the upper end of a water intake b^3 , the connection being preferably by means of screw-threads, the upper end of the intake forming the valve-seat, said intake being, in 5 vertical section, in the form of a three-way structure, providing opposing water inlets b^4 , said inlets combinedly being of an area greater than the area of a cross-section of the portion thereof which is secured to the 10 bottom, this construction providing against the formation of water currents when the valve is opened as hereinafter indicated. If desired the water inlets b^4 may be protected against the entrance of extraneous matter by 15 the use of suitable means, such as wire gauze, etc. The boss b^5 into which the intake b^3 is secured, preferably extends into the container, thereby providing an annular upwardly projecting portion around which the 20 valve cage b^6 is removably seated, the boss serving to prevent lateral movement of the cage when the parts are in position. The cage b^6 consists of a frame having a top b^7 to which is secured a rod b^8 , presently referred to, said cage having at its lower end an annular ring b^9 which loosely fits around the boss b^5 referred to. Connecting the portions b^7 and b^9 are a plurality of connecting strips b^{10} spaced apart and forming an open 25 work to permit of a free passage of the water therethrough. Within the cage b^6 a spider b^{11} is provided, said spider having an opening through which a valve stem b^{12} extends, said stem being adapted to receive the 30 valve b^{13} , said valve being seatable on the valve seat formed at the upper end of the intake. The stem b^{12} is of a length to project above the spider when the valve is seated and has its upper end provided with an 35 enlarged head b^{14} which is adapted to contact with the undersurface of the portion b^7 of the cage to limit the vertical movement of the valve. Said stem also projects below the valve, normally resting within the intake 40 45 as shown.

The top of the container is provided with an opening which registers with the opening at the bottom of the container, said opening at the top being of a size sufficient 50 to permit of the passage therethrough of the valve cage b^6 , said top having an upturned boss b^{15} formed by a nipple screwed into said opening, said boss having external screw-threads adapted to receive a screw-threaded cap b^{16} to which the upper end of the rod b^8 is secured in such manner that a 55 rotation of the cap b^{16} will cause a similar movement of the rod b^8 . By this construction of container, it will be readily seen that a 60 entire valve structure is bodily removable from the container through the opening at the top, the cap b^{16} being removed and forming a portion by means of which the entire structure including the valve and 65 its cage may be readily removed from the

container. When the valve and its cage are to be inserted within the container it will be readily understood that inasmuch as the container is closed with the exception of the opening at the top, that the centering 70 of the valve cage may prove tedious by reason of the fact that visual access thereto cannot be had, since the cap is necessarily so close to its boss that no opportunity is given for a seating of the cage. To aid in proper 75 seating of the cage the extended portion of the valve stem b^{12} is provided, said extended portion being of a length sufficient to cause the head b^{14} to contact with the top b^7 and prevent seating of the cap b^{16} should the 80 lower end of the stem b^{12} pass into contact with a portion of the bottom outside of the boss b^5 , unless the rod b^8 extends at such an angle as to prevent a proper entering of the 85 threads of the cap, this latter in itself indicating that the valve is not in proper position. If the stem passes within the intake, a swerving of the cage through manipulation of the cap will permit of readily finding the cage seat and positioning it thereon, 90 such positioning permitting the cap to be screwed into proper position. The top of the container is also provided with an opening adapted to receive the connections leading from the air pump A and to the pressure regulator C. The particular form of 95 securing these connections in position is not material, it being necessary only that an airtight joint connection be provided.

The pressure regulator C may be of any 100 desired type; it being understood that the regulator is provided with suitable mechanism operating in the nature of a valve to control the passage of water through the connection c' having its lower end extending 105 into the container at a point spaced above the bottom of the container. The end of the regulator is connected to one or more water outlets, indicated in the drawings by the spigot D.

It will be seen that when the container is properly positioned within the well, and the connections c' and the connection leading from the air pump to the container and designated as a' , are in position, the pressure of the water outside of the container will be sufficiently greater than the pressure exerted on the valve b^{13} to cause the latter to be raised and thereby permit entrance of the water into the container. For 115 the purpose of permitting a maximum amount of water to be introduced the connection a' is provided with a valve a^2 having an opening to the atmosphere, and which is herein designated as an air-escape or refilling valve, said valve a^2 being opened and permitting of the escape of air to reduce the pressure within the container which would be caused by the entrance of the 120 water therein. The entrance of water is 125 130

continued until it has reached a predetermined height whereupon the valve a^2 is closed and the air pump operated. Inasmuch as the connection a' extends but a 5 relatively short distance below the plane of the top of the container, it will be readily understood that an air space is formed at the top of the container, and the forcing of air within said space produces a pressure 10 within the container greater than that exerted by the water outside of the container with the result that the valve b^{13} is seated; and as the exit D is closed, no possibility is had of a discharge from the container 15 such as would affect the providing of a compression of air within the container of a predetermined number of atmospheres. In practice I have found that the apparatus herein disclosed will enable the user to 20 provide a pressure of one hundred pounds with ease and readiness. As this pressure can be imposed at any time by manipulation of the air pump and the structure of the container is such as to provide for a considerable 25 pressure, it will be readily understood that the device is especially applicable for use in suburban locations.

When the container has received its pressure, the opening of a spigot will immediately 30 reduce the pressure within the pressure regulator to an extent where the pressure from the container is greater than that within the regulator, thereby causing the regulator valve to be raised and permitting 35 water to flow from the container to and through the point of exit, this being continued as long as the spigot is open or until the pressure within the container is insufficient to elevate the water, or until the pressure 40 within the container is less than the regulating pressure of the regulator, the occurrence of this condition causing the regulator valve to be seated and remain seated irrespective of the opening of the spigot. 45 When this condition arises, it is necessary only for the operator to proceed to the air pump, open the refilling valve a^2 whereupon water will pass into the container in the manner heretofore set forth.

50 To permit of a release of pressure in the pump, I provide a pet cock a^3 which, when the valve a^2 is closed, may be opened to relieve pressure in the pump.

o^8 designates a pressure gauge for determining the pressure of water in the regulator and at the faucet.

Where the container has its axis extending substantially horizontally, it will be readily understood that the valve mechanism will 60 be located at the bottom of the container and therefore the valve stem will have its direction of length at approximate right angles to the axis of the container instead of in alinement with such axis as in the form in 65 which the container is provided with a verti-

cal axis as shown in the drawings. The operation, will, of course, be the same in either case.

The advantages of the construction herein described are thought to be clear and to 70 have been heretofore described.

Having thus described my invention, what I claim as new is:

1. In a water-elevating apparatus, a container having a water inlet extending 75 through and located above the plane of the container bottom, and also having a water outlet, means for providing an air pressure within said container, and a valve mechanism loosely mounted with respect to said 80 water inlet, said mechanism including a valve-carrier and a positioning device therefor extending through the container and removably secured to the top thereof, said device and valve being relatively positioned 85 to provide the valve-seat wholly upon said water-inlet, said device being formed to embrace the inlet end in normal position, the securing means for the positioning device forming a closure for the container. 90

2. In water elevator apparatus, a container having a water inlet at its bottom and also having a water outlet, a removable valve mechanism for said water inlet, said mechanism comprising a valve cage loosely 95 seated with respect to said water inlet, a valve carried by and removable with said cage for controlling said water inlet, and a cage-positioning device embodying a stem having one end secured to the cage and having its free end provided with a screw-threaded closure adapted to fit a screw-threaded opening on the upper side of the container, said stem being of a length to prevent engagement of the closure and its 100 seat when the cage is improperly positioned with respect to the inlet.

3. In water elevator apparatus, a container having a water inlet at its bottom and also having a water outlet, a removable valve mechanism for said water inlet, said mechanism comprising a valve cage loosely seated with respect to said water inlet, a valve carried by and removable with said cage for controlling said water inlet, and a cage-positioning device embodying a stem having one end secured to the cage and having its free end provided with a screw-threaded closure adapted to fit a screw-threaded opening in the upper side of the 110 container, said stem being of a length to prevent engagement of the closure and its seat when the cage is improperly positioned with respect to the inlet, said valve having a valve stem projecting below the seating 115 face of the valve to form a barrier against engagement of the closure and its screw-threaded opening when said cage is mispositioned. 120

4. In water-elevating apparatus, a con- 130

tainer having a water inlet at its lower end and an inwardly extending boss to which said inlet is secured, said container also having a screw-threaded opening opposite to 5 said inlet, a water outlet, a valve cage loosely fitting over said inlet boss, a valve mounted to move axially of said cage, said valve having its length of movement limited in one direction by the cage, a stem carried by the 10 cage and having its free end provided with a screw-threaded closure, adapted to coöperate with said screw-threaded opening of

the container, said stem being of a length to prevent engagement of the closure when the cage is out of its operative position, and 15 a water intake projecting below the bottom of the container and opening into the water inlet.

In testimony whereof I affix my signature in presence of two witnesses.

ROY H. RICHARDSON.
